US0D1105409S

(12) **United States Design Patent** (10) **Patent No.:** **US D1,105,409 S**
Chen (45) **Date of Patent:** **** Dec. 9, 2025**

(54) **DUST COVER**

(71) Applicant: **Shenzhen TPH Technology Co., Ltd.**, Shenzhen (CN)

(72) Inventor: **Xianzi Chen**, Shenzhen (CN)

(73) Assignee: **Shenzhen TPH Technology Co., Ltd.**, shenzhen (CN)

(**) Term: **15 Years**

(21) Appl. No.: **29/967,150**

(22) Filed: **Oct. 8, 2024**

(51) **LOC (15) Cl.** **24-02**

(52) **U.S. Cl.**

USPC **D24/109**

(58) **Field of Classification Search**

USPC D24/109, 107, 108, 121, 193-197, 127, D24/199; D7/900; D9/454

(57) **CLAIM**

The ornamental design for a dust cover, as shown and described.

DESCRIPTION

FIG. 1 is a front, left, top perspective view of a dust cover showing my new design;

FIG. 2 is a back, left, bottom perspective view thereof;

FIG. 3 is a front view thereof;

FIG. 4 is a back view thereof;

FIG. 5 is a left view thereof;

FIG. 6 is a right view thereof;

FIG. 7 is a top view thereof;

FIG. 8 is a bottom view thereof;

FIG. 9 is an enlarged view of the encircled area 9 of FIG. 2;

FIG. 10 is an enlarged view of the encircled area 10 of FIG. 4; and,

FIG. 11 is an enlarged view of the encircled area 11 of FIG. 5.

The dot-dash lines depict the enlarged view boundaries that do not form part of the claimed design.

1 Claim, 9 Drawing Sheets
